PAUL FABER, OF BADEN, SWITZERLAND, ASSIGNOR TO AKTIENGESELLSCHAFT BROWN,
BOVERI AND CIE., OF BADEN, SWITZERLAND

METHOD OF PRODUCING WATER FROM STEAM

Application filed January 4, 1928, Serial No. 244,492, and in Germany January 5, 1927.

Methods are known, in which the additional water of a steam boiler plant is evaporated by superheated boiler steam directly, for instance by introducing the superheated steam into the water or by injecting the water into the superheated steam. By this means the passage of heat through walls and dirtying of the latter is prevented. The production of distillate by means of superheated steam has the disadvantage, however, that only a limited quantity can be produced, even if all the working steam be used for the distillation. The superheating heat of the heating steam must be sufficient both for heating the arriving water up to the evaporating temperature and for supplying the evaporating heat of the water to be evaporated. The method according to the present invention, provides the possibility of producing any desired quantities of distillate by heating with superheated steam and by direct introduction into the water, the procedure being as follows. The superheated working steam coming from the steam boiler, or a portion thereof, is brought into contact in an evaporating vessel with the water to be evaporated, the superheating heat being transmitted to the water and evaporating a portion of the same. The quantity of steam thus increased, and consisting of the originally introduced heating steam and of the evaporated quantity of water, has the temperature of saturated steam and is reheated in a second superheater to a considerably high superheating temperature. This steam is thereupon conveyed to a second evaporating vessel where the increased quantity of steam, by giving off its superheating heat evaporates a larger quantity of water than in the first evaporator, which, in the form of steam, also becomes mixed with the heating steam. This quantity of steam can be again superheated and again used for evaporating water and so on, until the required quantity of water has been evaporated. The quantity of working steam is then conveyed directly to the point where it is to be used. The remaining quantity of steam corresponds to the evaporated water and is condensed in a condenser. The condenser may for instance be used as a heater for the water.

In the accompanying drawing a constructional example is shown diagrammatically. In this drawing 1 is the steam boiler, 2 the superheater, 3 the first evaporator, 4 the second superheater, 5 the second evaporator and 6 the third superheater, for superheating the working steam. 7 is the feed water pipe, through which the water is introduced into the evaporators 3 and 5. 8 is the condenser in which the required liquid distillate is produced. In the example shown the water is used for cooling the condenser. The valve 9 enables the quantity of distillate produced to be varied.

What I claim is:

1. A method of producing distillate from steam which comprises evaporating a quantity of saturated steam in a boiler, superheating said saturated steam in a superheater and injecting same into a quantity of water contained in an evaporator to form an augmented quantity of saturated steam corresponding to the heat units introduced into the evaporator and leading at least part of said augmented quantity of saturated steam into a condenser where it is condensed. 65

2. A method of producing distillate from steam as claimed in claim 1 wherein the steps of superheating and subsequent evaporating are repeated. 70

3. A method of producing distillate as claimed in claim 1 wherein the cooling water for the said condenser is utilized for feeding the evaporator. 75

4. A method of producing distillate as claimed in claim 1 wherein the proportion of the augmented quantity of saturated steam is regulable. 80

In testimony whereof I have signed my name to this specification.

PAUL FABER.
